UNITED STATES PATENT OFFICE.

GEORGE HUGH FOSTER, OF MARRICKVILLE, NEW SOUTH WALES, AUSTRALIA.

WALL-PLUG FITTING.

1,117,654.

Specification of Letters Patent.

Patented Nov. 17, 1914.

Application filed May 2, 1913. Serial No. 765,140.

To all whom it may concern:

Be it known that I, GEORGE HUGH FOSTER, a subject of the King of Great Britain and Ireland, residing at The Palms, Marrickville 5 Road, Marrickville, in the State of New South Wales, Commonwealth of Australia, have invented certain new and useful Improvements in Wall-Plug Fittings, of which the following is a specification.

10 This invention relates to wall plugs incased within a metallic tube and laid in brick or masonry jointing during building construction and used for fixing interior finishing such as door frames, window frames, 15 architraves, skirting boards and the like.

The object of the invention is to effect such improvements in plugs of the type and for the purpose mentioned, that the same are also adapted to be fitted into a drilled hole 20 in the wall and secured by grouting and the casing ends also utilized for securing interior or exterior fitments thereto, and further the plugs are prevented from being driven 25 farther into the metallic casing containing same.

To this end the invention consists in the employment of the peculiarly constructed casing or hollow bolt for the plugs and the end structural arrangements of said casing 30 or hollow bolt all as hereinafter fully described and claimed, and as illustrated in the accompanying drawings wherein:—

Figure 1 is a perspective view of one form of improved plug; Fig. 2 a longitudinal section thereof; Fig. 3 a cross section on line 3—3, Fig. 2. Figs. 4, 5 and 6 are perspective views of two further and modified forms of plugs. Figs. 7 and 8 are longitudinal sections of Figs. 5 and 6. Figs. 9 and 10 are 40 sectional views of plugs in use; Fig. 11 a perspective view of a slotted clip for use with the plug casing. Fig. 12 a sectional view thereof.

The metallic tubular casing 13 has threaded ends 14 for the nuts 15 and is provided with a core or plug 16 in each end of wood or other suitable substance. As shown in Figs. 1, 2 and 3 the tube 13 is somewhat flattened as at 17, thereby forming a stop and preventing the plugs 16 from being driven into the casing 13. In assembling the parts 50 13 and 16 the casing 13 is first flattened at 17 and the plugs 16 then inserted.

The casing 13 shown in Fig. 4 has double

flattened portions 17, and would be used 55 principally for very thick walls.

In Figs. 5, 6, 7 and 8 the casing 13 has a flanged head 18, flattened portion 17, and nut 15, while also as in Figs. 6 and 8 the flange has a lip forming a receiving cup 19 60 into which grouting is poured when the plug is inserted into a drilled hole.

Referring to Figs. 11 and 12 the clip 20 has an elongated slot 21 for the plug end 14 and has a circular lug or tenon 22 adapted to 65 take into a corresponding recess or mortise 23 similar in shape, in the door jamb lining 24. This lug or tenon 22 has an orifice 25 for the screw 26.

In use the casing 13 is laid into a joint 70 during building operations, and when ready for the wood-work to be attached the nuts 15 are tightened, and thus as shown, the skirting boards 27 being fastened by the 75 nails 28.

When the casing 13 is inserted into a drilled hole 29 (see Fig. 10) grouting is poured into the cup 19 thereby filling up the drilled hole 29 around the plug. The clips 20 are fastened to the wall by the plug, casing nuts 15 (see Fig. 12) and to the door jamb 24 by screw 26.

The architraves 30 are affixed to the jamb lining 24 and to the plugs 16 in the usual manner.

What I claim and desire to secure by Letters Patent is:—

1. In a wall plug, in combination, a metallic tubular casing containing plugs, deformed portions in said casing intermediate its ends 90 forming stops for said plugs, a flanged head at one end of said casing and a nut at the opposite end of said casing, and a lip on said flanged head as and for the purpose set forth.

2. In a wall plug, in combination, a metallic tubular casing containing plugs, flattened portions intermediate the ends of said casing forming stops for said plugs, a nutted end on said casing, and a slotted clip or plate adapted to receive the nutted end of said casing and means for securing said plate to the wall, as and for the purposes set forth.

Signed at Sydney, New South Wales, this twentieth day of March 1913.

GEORGE HUGH FOSTER.
